UNITED STATES PATENT OFFICE.

CHAUNCEY R. BENEFIELD, OF ALPIKA, MISSISSIPPI.

COTTON ELEVATOR AND SEPARATOR.

SPECIFICATION forming part of Letters Patent No. 705,374, dated July 22, 1902.

Application filed March 5, 1901. Serial No. 49,881. (No model.)

To all whom it may concern:

Be it known that I, CHAUNCEY R. BENEFIELD, a citizen of the United States, residing at Alpika, in the county of De Soto and State of Mississippi; have invented a new and useful Improvement in Cotton Elevators and Separators, of which the following is a specification.

My invention is an improvement in that class of pneumatic elevators by which cotton and similar substances are raised and then released and deposited at a selected point by variation of air-pressure.

The feature of novelty is hereinafter described in connection with other co-operating parts.

In the drawings, Figure 1 is a sectional elevation on the center line of the apparatus. Fig. 2 is an elevation on the line 22 of Fig. 1. Fig. 3 is a horizontal section on the line 33 of Fig. 1.

The apparatus includes a tubular curved chute provided at its lower end with a cloth or other flexible valve B, shown open in the views, which is adapted to close automatically after the discharge of certain weight of cotton from the chute.

C is an air-suction pipe leading to a suction-fan. (Not shown.)

D is a screen which is arranged in the upper curved portion of chute A, and serves to separate the trash and dust from the cotton. This screen is separated from the upper side of the chute by a narrow space into which the dust is received and conducted to pipe C.

E are arms extending horizontally in the portion of the cotton-pipe A leading from the wagon or other supply, and the same are provided with teeth G, extending downward and serving to straighten the cotton and loosen the dirt and sand from same. These arms E are spread out fan-shaped, as shown in Fig. 3, so that they spread the cotton laterally and distribute it evenly over the entire screen D, thus bringing into use a larger screening-surface and more thoroughly removing dirt and sand.

I indicates a glass-covered opening or window to permit observation of the cotton held

against the screen D and in the cotton-chute 50 A. The screen D is so curved that the cotton and air carrying the same strike the inner surface of the screen tangentially, and by so doing the cotton is at the same time given an impetus downward, which causes it 55 to drop into the cotton-chute A, while the dust and sand pass through the screen and are carried off into pipe C. It will be understood that when a sufficient amount of cotton has been deposited in the chute A its 60 weight overcomes the suction or tension due to the suction of the air, and it drops and passes through the valve B. This valve is formed of a cylinder of fabric and is kept from sucking up into the chute A by fixed 65 arms J, that extend downward from the chute and are fastened to the cloth at K.

In operation the cotton-pipe F is duly extended and connected to the cotton-supply in the wagon or other receptacle, and the suction-fan (not shown) connected to the pipe C is put into action, whereby cotton is drawn into F, past the toothed bars E, and against the screen D by which the dust and sand are extracted and the cotton given a downward 75 impulse, which being resisted by gravity dislodges the cotton from the screen and causes it to drop into the vertical part of chute A. When a sufficient quantity of cotton has accumulated in the chute, it overcomes the 80 suction in the pipe C and drops downward, opening the valve B. When the valve B is relieved of the weight of cotton in the chute A, it is again closed by the suction of the air and the cycle of operations is again begun. 85

A flat pivoted valve H is arranged in the side of air-suction pipe C, so that the tension of the vacuum may be relieved manually and at will, as when the quantity or weight of cotton held in the chute A is too small to 90 cause automatic discharge. The valve H is operated by cords K'.

It will be understood that the closure of the valve B is effected automatically by contraction or puckering of its free end. 95

What I claim is—

In a pneumatic elevator of the class described, the combination with the chute, a

screen, a cotton-receiving pipe, of a series of bars arranged horizontally and with their inner ends diverging, the same being provided with hooks, substantially as shown and described, whereby the cotton is spread laterally and distributed in the manner specified.

In testimony whereof I have signed my

name to this specification in the presence of two subscribing witnesses.

CHAUNCEY R. BENEFIELD.
